MULTIPLE PANEL DISPLAY BOARD

William G. Damroth, New York, N. Y., assignor
to Hile-Damroth, Inc., New York, N. Y., a corporation of New York

Application February 11, 1947, Serial No. 727,754

3 Claims. (Cl. 40—125)

1

The present invention relates to display boards and more particularly to a board formed of a plurality of separate panels which can be used singly or can be aligned in edge-to-edge co-planar relation and secured together to provide a single board having one dimension equal to that of a single panel and having another dimension equal to that of any multiple of the corresponding other dimension of a single panel.

While the invention is capable of embodiment in display boards generally and, indeed, in other articles of manufacture analogous to display boards, it is particularly adapted to be embodied in visual demonstration or presentation boards of the type generally referred to in the copending application of James L. Hile, Ser. No. 687,589, filed August 1, 1946, entitled Display Device. Such boards are characterized essentially by a facing of fibrous fabric, such as a woven or felted material, on which indicia elements may be separably mounted by adhesive, thumb tacks or other conventional means, or by the interengagement of the fibers of the board facing with granules forming the backing of the indicia elements, in accordance with the Hile invention.

A principal object of the present invention is to provide a board of the character indicated which can be made effectively extensible in one dimension, which may be its length or width, by securing separate panel elements together in edge-to-edge co-planar relation.

A related object is to provide a board which can be knocked down or disassembled for purposes of transportation or storage into a space much smaller than that occupied by the board when set up.

A further object is to provide a plural-panel board with simple, effective durable and economical means by which the panels can be quickly connected and disconnected.

Another object is to provide such a board with means for securing the panels together in such a way that the assembled panels will be held against edgewise separation in their common plane and against movement relatively to each other to an angular relationship less than that of a straight angle.

Other and further objects and advantages of the invention will be evident from the following description of a preferred embodiment which is illustrated in the accompanying drawing and which has been tested in actual practice and found entirely satisfactory so that it is at present preferred by me as the best mode in which I contemplate applying the principles of the present invention.

In the accompanying drawing:

Figure 1 is a front elevational view of a plurality of panels assembled to provide a single board;

Fig. 2 is an end elevational view of the board;

Fig. 3 is a rear elevational view of the assem-

2

bled panels, shown on a relatively enlarged scale;

Fig. 4 is a detail rear elevational view, on a further enlarged scale, showing a portion of the joint between adjacent panels, provided with means for stiffening the joint;

Fig. 5 is a cross-sectional view, taken on the line 5—5 of Fig. 4; and

Fig. 6 is a detail rear elevational view similar to that of Fig. 4 but showing the means for holding the adjacent panels against edgewise separation in their common plane.

Referring to these figures, the illustrated embodiment of the invention includes a plurality of panels, all made in generally similar fashion, designated 1, 2, 3 and 4. Each of these panels is best made in the form of an outer frame of wood or the like composed of four rails, nailed, glued or otherwise connected to form a rectangular outline. This framework may be faced and covered on one side by a sheet of comparatively stiff material, such as cardboard, fiber board, thin wall board, plywood or the like, designated 5, which in turn may be covered by surfacing material 6 consisting of the fibrous woven or felted fabric hereinabove referred to. The margins of this fabric may be turned under the edges of the sheet 5 and glued thereto, and the composite sheet may be secured to the framework by tacking, gluing or in any other appropriate way.

The result is a rectangular panel bounded by wooden rails 7 at the top, 8 at the bottom and 9 and 10 at the respective sides. This assembly may be completed by an intermediate cross rail 11 spanning the approximate center of the frame to increase its rigidity and for a further purpose hereinafter to be explained.

In order to provide a snug fit between adjacent panels in the assembled board, and to assist in aligning the panels accurately in a single plane when they are set together in edge-to-edge abutting relation, the side rails 9 and 10 may be respectively tongued as shown at 12 and grooved as shown at 13 in Fig. 5. However, since these tongues and grooves function only in joining together adjacent panels, those panels which are intended to be outermost of the assembly, such as the panels 1 and 4 in the illustrated embodiment, may have their extreme outer rails, such as the rails 10, made plain, without any tongue or groove.

The panels are provided with means for securing them together in such a way that they cannot be pulled apart and cannot move relatively to each other to an angular relationship less than that of a straight angle. Such means is provided, according to the present invention, in the form of a stiffening bar which spans each joint, in combination with a tension element which holds the adjacent panels against edgewise separation.

I have found it convenient to provide the stiff-

fening bar in the form of a conventional type of bolt 14 slidably mounted in a bearing 15 which is secured to one panel so that the bolt can be extended across the joint and be inserted in a keeper 16 which is secured to the adjacent panel. Each of the panels is provided with such a bolt or keeper. Those panels, such as the ones designated 2 and 3 in the drawing, which are intended to occupy an intermediate position in the assembled board, are provided with both a bolt and a keeper, but those panels, such as the ones designated 1 and 4, in the drawing, which are intended to occupy an end position in the assembled board, may have only a bolt or only a keeper, all as is illustrated in Fig. 3. 15

The bolts and keepers may be mounted directly on the side rails 9 and 10, but it is preferable to mount them on the intermediate stiffening rails 11 because the side rails are best made relatively narrow and hence do not provide adequate mounting surface, as do the intermediate rails.

The tension means, for preventing edgewise separation of the panels, is conveniently provided in the form of hooks, such as are shown at 17 mounted on a side rail 9 or 10 of each panel, for cooperation with a hook-receiving element, such as an eye or stud 18, mounted on the side rail 10 or 9 of each adjacent panel. As in the case of the bolts and their keepers, it is unnecessary to form any hook or hook-receiving element on the outer side rails of the end-most panels.

The hooks and the bolts are best separated considerably along the length or height of the panels, so that the stiffening effect of each bolt is obtained at some distance from the connecting effect of each hook. However, it is not essential that these two kinds of fasteners be mounted precisely as shown in the drawing or that they be spaced exactly as there shown.

All or some of the panels may optionally be provided with struts or props 19 hinged at 20 to the top rails 7 and braced to one of the side rails or to the cross rails by a jointed bracket 21, so that the board may be self-supporting as an easel. In addition, each or some of the panels may be provided with an eye or hook 22, like those shown projecting from the top rails 7 of the end panels 1 and 4, by which the assembled structure may be hung on a wall. This hanging is easily accomplished because the combined actions of the stiffening and tension means rigidifies the entire structure and prevents its collapse or disassembly regardless of where or how the structure is held.

It will be observed that if the composite facing sheets formed by the elements 5, 6 extend more or less accurately to the plane of the edges of the side rails 9, 10, the joint between adjacent panels of the assembled board is rendered inconspicuous, so that there is no appreciable break in the over-all surface of the assembly. For this reason indicia pieces, even when they are quite small in size or area, can be attached anywhere on the assembly surface, including directly over the joints.

While the invention has been described in terms of display boards, and more particularly for embodiment in the type of display board generally referred to in the Hile patent application, it will be recognized that the principles of the invention are equally adapted for embodiment in other more or less analogous kinds

of structures in which it may be desirable to associate a series of panels in edgewise connected relation to increase the effective width or other dimension of the series.

5 The principles of the invention are pointed out by the appended claims, in which the number of the panels is defined as a pair. This, of course, is not intended to limit the scope of the invention to the use of two panels only, but is intended to cover all embodiments of the invention in which a plurality of panels may be used, since any plurality of cooperating panels, such for example as the four shown in the drawing, necessarily includes a pair.

I claim:

1. A display board comprising a pair of separate panels each provided along one edge with a frame member having a configuration adapted to interlock with the frame member of the other panel when the two panels are abutted edgewise in co-planar alignment, in combination with cooperating hook and eye means carried respectively by the adjacent frame members of the two panels for holding said panels against edgewise separation in their common plane, and cooperating bolt and keeper means carried respectively by the surfaces of said frame members whereby the bolt may be extended into the keeper to span the joint between the panels and stiffen said joint so as to prevent movement of the panels relatively to each other to an angular relationship less than that of a straight angle.

2. A display board comprising a pair of separate panels having tongued and grooved side frame members for interlocking mutual engagement when the two panels are abutted edgewise in co-planar alignment, in combination with cooperating bolt and keeper means carried respectively by the surfaces of said frame members whereby the bolt may be extended into the keeper to span the joint between the panels and stiffen said joint so as to prevent movement of the panels relatively to each other to an angular relationship less than that of a straight angle.

3. A display board comprising a pair of separate panels having side frame members provided respectively with a projection and a recess adapted to interfit when the two panels are abutted edgewise in co-planar alignment, hook

50 and eye means carried respectively by the adjacent frame members of the two panels for holding said panels against edgewise separation in their common plane, an intermediate cross rail connecting the side frame members of each 55 panel, the cross rails of adjacent panels being aligned when the panels are abutted, and cooperating bolt and keeper means provided on the respective cross rails of adjacent panels whereby the bolt may be extended into the keeper to span the joint between the panels and stiffen said joint so as to prevent movement of the panels relatively to each other to an angular relationship less than that of a straight angle.

WILLIAM G. DAMROTH.
